CLEANER FOR POWER-DRIVEN ROTARY
HAND TOOLS, ESPECIALLY DENTAL
BURRS

Elmore E. Buskirk, Adrian, Mich.

Application January 5, 1946, Serial No. 639,435

2 Claims. (Cl. 21—82)

1

This invention relates to sanitation and upkeep equipment features, more particularly for tools as requiring extended use in surgery.

This invention has utility when incorporated in mechanical cleansing and sterilizing of cutting tools of the burr type, as in dental surgery.

Referring to the drawings:

Fig. I is a side elevation, with parts broken away, of an embodiment of the invention for brush cleaning and simultaneously sterilizing a dental burr, shown as thrust thereto for reciprocation during rotation thereof;

Fig. II is a plan view of the cleansing and sterilizing device of Fig. I; and

Fig. III is a section on the line III—III, Fig. II, showing the device or unit in released position, and thereby differing from the showing in Fig. I.

A yieldable rim or base member 1 may function as a suction cup mounting or anchor for an open top cup or vessel having a bottom 2 at the suction cup region, and cylindrical riser 3 therefrom to an open top 4.

Adapted to be inserted telescopically into the cylindrical riser 3 is a cylindrical wall 5 of an inverted cup having a top wall or end 6. Centrally of the top 6 is a guide way or slot 7 as an opening. Projecting from opposite sides of a lane into meeting and mutually intercepting relation below the slot 7 of the top 6 are bristles 8 from brush backs 9 having upstanding screws 10 extending thru slots 11 in the top 6 extending away from the slot 7. Accordingly the screws 10 may be operated to release the brush backs 9 for adjustment toward or away from the slot 7 into more or less close interfitting relation for the bristles 8, or to take up for wear on the bristles due to extended operation or use hereunder.

A light readily yieldable helical spring 12 is in the inverted cup chamber 13 bounded by the cylindrical side 5 and acting from the bottom 2 to thrust against the under side of the top wall 6. The spring 12 in the chamber 13 is clear of the central brush region 8, 9.

Sufficiently down as not to overflow the open top 4, there is a charge 14 of liquid sterilizing medium in the chamber of the upwardly open cup 2, 3. With the inverted cup 5, 6, thereover, the slot 7 allows the sterilizing liquid 14 to seek its own level as the same both inside and outside of the wall 5. The spring 12 now poises the inverted cup 5, 6, upward sufficiently clear of the liquid 14 to have the brushes 8, 9 not submerged in the liquid. Accordingly, in practice, the brushes 8, 9, are normally dry and as dry are more stiff or rigid for cleansing action, which stiff

2

or rigid condition persists for efficient functioning when momentarily submerged, for such is not of time duration sufficient to soften up the bristles to impart more flexibility thereto.

The dental surgeon, or operator, retaining a normal directing grasp at a tool handle 15 may locate its angle drive clutch end fitting 16 to project a tool or burr 17 thru the slot 7 in the top 6, and thrust the burr 17 back and forth as the underside of the fitting 16 rides along the edges of the slot 7 lengthwise thereof. In practice, the tool handle 15 is a terminus for a flexible conduit or shield 18 in which is located a rotating flexible shaft 19. A source of driving power, as an electric motor, or even treadle, may provide the rotation drive for the shaft 19.

Should the operator, in thrusting the burr 17 into the slot 7, exert no downward pressure, but merely reciprocate the burr 17 as now rotating past the bristles 8, the burr 17 rotation effects an efficient burr exposure, supplementing the back and forth movement, to clear the burr 17 of any adherent particles and give it a mechanical dry cleaning. However, the usual practice is for the operator to act to overcome the slight lifting action of the spring 12. By so depressing the top 6 thru pushing the fitting 16 down to ride along the sides of the slot 7, the brushes 8, 9, are at least to some extent submerged in the sterilizing solution 14. Now, the back and forth movement imparted to the fitting 16 by the hand of the operator, supplemented by the spinning motion imparted by the rotating shaft 19 to the burr 17, brings about a sterilizing washing almost instantaneously. The treated, as well as cleaned tool thus is an important factor in speeding up dental service.

Especially in surgical practice, importance resides in sanitary upkeep of equipment. Should the drill or burr break thru into a disturbed region of infection in the mouth of a patient, the operator may at once thrust the burr 17 thru the slot 7, and as depressed into the liquid 14, effect efficient sterilizing cleansing so that he may continue working with the same tool. When the tool is taken from the mouth of the patient, the tool may be thrust into the slot 7, and while still rotating, the handle moved back and forth in the range of positioning as determined by the bounds for the slot 7 as a seat for the holder or fitting 16. With sufficient down pressure to overcome the spring 12, the brush means 8, 9, are brought into cooperating relation with the bath provided by the sterilizing solution 14. Efficient sterilized cleansing of the tool or burr 17 is quickly had,

and the work upon the patient may proceed as though a new tool were installed. Furthermore, this rapid clearing of foreign matter from the tool promotes tool life against deleterious attack upon the tool as well as contributes to retention of initial cutting values of the tool.

It is desirable that the bristles of the brush means 8 so project into the lane under the slot 7 in their border location along the slot 7 for the bristles 8 at least to some extent intermingle at their ends. The top 6 with the screws 10 provides a mounting for the brushes 8, 9. The spring 12 responds to depressing action thru the holder 15, 16, on the seat about the slot 7, for the liquid 14 to enter into scrubbing or washing action thru the bristles 8 upon the tool 17.

Upon lifting of the handle 15 and clearing of the tool 17 from the cleaner, the spring 12 at once elevates the brushes 8, 9, clear of the solution 14, for the bristles to drain dry. Accordingly, a succeeding use of the cleaner of this invention may be with or without the bath action of the solution 14 in the housing, depending upon whether the mounting 6, 7 be depressed or left up, as the tool 17 is brought thereto.

What is claimed and it is desired to secure by Letters Patent is:

1. An open top cup providing a receptacle adapted to be partially filled with a treating solution, in telescopic relation therewith an inverted cup having a slot in the top providing a guide way, brush means depending from the top on opposite sides of the way with bristle portions therefrom in intersecting relation, and a spring

coacting between the cups normally to hold the brush means upward from the solution, whereby a rotary tool may be thrust thru the slot past the brush means to depress the brush means into the solution with the tool directed for lateral reciprocation by the slot as a guide.

2. A pair of relatively telescopic cups, one having a closed bottom and the other a slotted top with brush means inward along the sides of the slot, and a spring poising the slotted top away from the closed bottom to have the brush means clear of a treating solution charged into the closed bottom cup, whereby the slot provides a guide way for a tool to be slid therealong while protruding into the brush means and depressible to extend to the solution.
